(57) **CLAIM**

The ornamental design for a chum bait dispenser, as shown and described.

DESCRIPTION

FIG. 1 is a front perspective view of a first embodiment of a chum bait dispenser.

FIG. 2 is a rear perspective view thereof.

FIG. 3 is a front elevation view thereof.

FIG. 4 is a rear elevation view thereof.

FIG. 5 is a right-side elevation view thereof.

FIG. 6 is a left-side elevation view thereof.

FIG. 7 is a top plan view thereof.

FIG. 8 is a bottom plan view thereof.

FIG. 9 is a rear perspective view of thereof, showing the chum bait dispenser in a position of use with exemplary bait and an exemplary cutting device.

FIG. 10 is a right-side elevation view thereof showing the design with an environmental cap.

FIG. 11 is a rear perspective view thereof.

FIG. 12 is a front perspective view of second embodiment of a chum bait dispenser.

FIG. 13 is a right-side elevation view thereof; and,

FIG. 14 is a top plan view thereof.

The broken lines are shown for the purpose of illustrating environmental subject matter, including a cap, bait, a cutting device, and a user's hand. None of the broken lines form part of the claimed design.

1 Claim, 12 Drawing Sheets
